UNITED STATES PATENT OFFICE.

WILLIAM A. DOBSON, OF BRIDGEPORT, CONNECTICUT, ASSIGNOR TO UNDERWOOD
ELLIOTT FISHER COMPANY, OF NEW YORK, N. Y., A CORPORATION OF DELAWARE.

TYPEWRITER-CARRYING-CASE LOCK.

Original application filed March 21, 1923, Serial No. 626,457. Divided and this application filed November 22, 1926. Serial No. 149,853.

This invention relates to carrying cases for portable typewriting machines. Such carrying cases usually consist of a cover and a base to which the machine may be secured, and to 5 which the cover may also be locked.

Heretofore the cover has been provided with hooks that necessitated placing the cover on end on a support, after which the base was tilted to set its rear end into the hooks.

10 Careless handling during this tilting of the base often caused injury to the paper-table or other of the carriage-parts of the machine by striking them against either the cover or its support. To overcome this, the method of 15 attaching the cover to the base has been changed by this invention, so that it is no longer necessary to tilt the base or lift it from its support while assembling the cover thereon.

20 With the cover-fastening means provided herein, the base may be set flat on a table or other support. The cover is then grasped by the handle and tilted in back of the base with its lower rear edge resting on the table, 25 the cover is then drawn forward over the base until its rear edge strikes the rear edge of the base, and the fastening means becomes engaged. The front of the cover is then lowered, so as to overlap and enclose the edges of 30 the base, and the locking means engaged.

Thus it is only necessary to use one hand in placing the cover on the base and locking it thereto. By holding the handle of the cover with only one hand, the cover may readily

35 be hooked to the base and also swung down and made to lock itself automatically to the base. In other words, the user may simply pick up the cover by its handle, both hook and lock the cover to the base, and walk away 40 with the machine in his hand, all without releasing his grasp of the handle.

Another object of the invention is to provide a combined locking and automatic latching means to retain the cover on the base.

45 Both the attaching means and the locking and latching means are simple in design, easily and rapidly assembled and installed, and inexpensive to manufacture, and yet are extremely efficient in performing their various functions.

This application is a division of my application, Serial No. 626,457, filed March 21, 1923, (now Patent No. 1,646,952, dated October 25, 1927).

Other features and advantages will here- 55 inafter appear.

In the accompanying drawings,

Figure 1 is a front elevation of a type- 60 writer-carrying case, showing the cover locking and latching means attached thereto.

Figure 2 is a view of a cross-section on the line 2—2 of Figure 1, showing the means for securing the cover of the case to the rear end of the base.

Figure 3 is a front elevation of a portion 65 of a typewriter-carrying case, showing the cover partly closed over the base, and showing the front escutcheon of the lock removed to disclose the lock mechanism.

Figure 4 is a front elevation, similar to 70 Figure 3, showing the cover fully closed and latched.

Figure 5 is a view of a cross-section on the line 8—8 of Figure 4.

Figure 6 is a front elevation, similar to 75 Figure 3, showing the cover fully closed, latched and locked.

Figure 7 is a view of a cross-section on the line 10—10 of Figure 6.

Figure 8 is a perspective view of all of the 80 parts which make up the locking means for the cover of a typewriter-carrying case, showing the method of assembling them in the cover.

Figure 9 is a perspective view of the rear 85 escutcheon of the lock, which indicates the manner in which parts of the lock are assembled thereon.

Figure 10 is plan view of the latch-actuating 90 knob.

Figure 11 is a side elevation of the latch- 95 actuating knob, showing the head in section.

A typewriter 15, having a carriage 16, is fastened in a case 17, which is made up of a base 18 fitted with feet 19, and a cover 20 fitted with a handle 21. Corner-pieces 22 may be fastened in the corners of the cover 20 to act as stops to limit the distance that the cover 20 may be pushed over the base 18. In the rear edge of the base 18 are recesses 23, which extend from the top surface to the bottom surface of the base 18, where they join adjacent concave recesses 24, in the bottom surface, as shown in Figure 2.

Fastened in the recesses 23, by means of 105 screws 25, are wear-plates 26 having bottom edges 27 bent at an angle and to a concave form to register with the concave recesses

24 into which they extend. Rivets 28 hold strips 29 in position on the lower inside edge of the back of the cover 20 at points adjacent to the wear-plates 26. Prongs or detents 30, formed on the lower ends of the strips 29, are bent inwardly to engage the wear-plates 26, as shown in Figure 2.

In assembling, the base is placed flat on a table. With its forward edge uplifted and its lower rear edge resting on the support, the cover 20 is grasped by its handle 21 and drawn forward over the typewriter 15 and the base 18 until the prongs or detents 30 are engaged with the wear-plates 26. When the cover is lowered, the rear edge of the base 18 will be firmly held between the lower ends of the corner-pieces 22 and the prongs or detents 30.

The front of the cover 20 has an opening 31 in its lower edge, as shown in Figure 8, in which is positioned a combined locking and automatic latching means 32, having a front escutcheon 33 and a rear escutcheon 34, connected by shouldered rivets 35 that pass through holes 36 in the escutcheons 33 and 34 and the cover 20. Located on the vertical axis of the front escutcheon 33, near its top edge, is an opening 37 into which is fitted the shouldered front end of a barrel 38. The lower edge of the opening 37 has a slot 39 depending therefrom to allow a bit 40 of a key 41 to pass into the barrel 38. The lower edge of the front escutcheon 33 is bent backwardly to form a bottom 42, and upwardly to form an upstanding edge 43, in back of which the lower edge of the rear escutcheon 34 is confined when assembled on the cover 20. In the bottom 42 of the front escutcheon 33 is the head 44 of a T-shaped slot 45, the long leg 46 of which extends upwardly into the upstanding edge 43, as shown in Figure 8. The front edge of the base 18 is provided with a wear-plate 47, fastened in place by screws 48, and serving as a support in which is fastened a latch-pin 49, which has a head 50 and a shank 51, which, during the latching operation, as the cover is swung down to overlap and enclose the edges of the base, enter the head 44 and the long leg 46, respectively, of the T-shaped slot 45. The rear escutcheon 34 has an opening 52 on its vertical axis, near its top edge, corresponding with the opening 37 in the front escutcheon 33, to receive the other shouldered end of the barrel 38. To the left of, and approximately midway between, the opening 52 and the top edge of the rear escutcheon 34 is another opening 53 to receive a flat-headed rivet 54, on which is pivoted a latch 55. Near its free end the latch 55 is provided with a limit-slot 56, which permits sidewise movement of the latch 55 on a flat-headed limit-pin 57. Just above the limit-slot 56, the latch 55 is provided with an offset pin 58, on which is seated a spring 59, which

holds the latch 55 in latching position. The free end of the latch 55 is provided with an open slot 60 designed to receive the shank 51 of the latch-pin 49. A hook 61, formed on the free end of the latch 55 by the open slot 60, serves to prevent upward movement of the cover 20 from the base 18 when the latch 55 is in latching position, and an inclined face 62, on the front or open side of the hook 61, provides an automatic displacing means for the latch 55 when the cover 20 is lowered to position on the base 18. In the back or closed part of the hook 61, opposite the open slot 60, is a tapped hole 63 into which is screwed the threaded end 64 of a latch-operating pin 65. The shank 66 of the operating pin 65 passes through an operating slot 67 in the front escutcheon 33, and terminates in a thumb-nut 68 which is provided with a corrugated concave face 69.

When it is desired to merely latch the cover 20 without locking it, the various parts of the locking and latching means 32, already described, are in the positions shown in Figure 4.

To open the case, it is only required to move the thumb-nut 68 to the right, which will move the latch 55 in corresponding direction against the tension of the spring 59 and thereby disengage the hook 61 from the latch-pin 49.

To lock the cover 20 in closed position on the base 18, the locking and latching means 32 is provided with a bolt 70 movably mounted in a bolt-case 71. The bolt-case 71 is provided with anchor-lugs 72, which are seated in corresponding anchor-lug slots 73 in the rear escutcheon 34. An opening in the bottom of the bolt-case 71, at 74, permits free passage of the bolt 70, and a stop 75, adjacent to the opening at 74, is designed to engage a long notch 76, near the lower end of the bolt 70, which terminates in a shoulder 77. The shoulder 77 abutting against the stop 75 serves to limit the downward movement of the bolt 70. Another long notch 78, near the upper end of the bolt 70, terminating in a shoulder 79, engages a stop 80 formed on the inside of the front face of the bolt-case 71. The shoulder 79 abutting against the stop 80 serves to limit the upward movement of the bolt 70. The stops 75 and 80 engaging the long sides of the notches 76 and 78 also serve to hold the opposite side of the bolt 70 against the barrel 38, so that the bit 40 of the key 41 will register with shoulders 81 and 82 of a key-notch 83 in the bolt 70. The bolt-case 71 is cut away at 84 to give free passage to the key-bit 40. Just below this cut at 84 on the bolt-case 71 is a pin 85 to receive the other end of the spring 59 which holds the latch 55 in latching position. In the side of the bolt 70, opposite the key-notch 83, are two tumbler-notches 86 and 87 to

receive a detent 88 on a tumbler 89, which, in the preferred form, is made of a leaf-spring.

To lock the cover 20 after latching it, with the parts of the locking and latching means 32 positioned as shown in Figure 4 of the drawings, the key 41 is inserted in the barrel 38 and turned to the right. The bit 40 strikes the shoulder 82 of the key-notch 83 and forces the bolt 70 downwardly until a notch 90 near its lower end engages a flat surface 91 on the latch 55, thus preventing movement of the thumb-nut 68 to release the latch 49 from the hook 61. The parts will then be in the positions shown in Figure 6. This action will release the detent 88 of the tumbler 89 from the tumbler-notch 87 and seat it in the tumbler-notch 86, in which position it will tend to restrain all movement of the bolt 70, except that imparted by the key 41.

Turning the key 41 to the left will bring the bit 40 into engagement with the shoulder 81 of the key-notch 83, and will force the bolt 70 upwardly to release the latch 55 and restore the parts to the latching position shown in Figure 4.

Variations may be resorted to within the scope of the invention, and portions of the improvements may be used without others.

Having thus described my invention, I claim:

1. A lock for a typewriter-carrying case including a baseboard and a cover, in combination, a latch-pin mounted on one edge of said base-board, latching means mounted in a wall of said cover to co-operate with said latch-pin to automatically latch said cover to said base-board when said cover is swung down to overlap and enclose the edges of said base-board, and means to lock said latching means to prevent the opening of said cover.

2. A lock for a typewriter-carrying case including a baseboard and a cover, in combination, a wear-plate, having a latch-pin with an enlarged head mounted thereon, fastened to one edge of said baseboard, latching means mounted in a wall of said cover to co-operate with said latch-pin to automatically latch said cover to said baseboard when said cover is swung down to overlap and enclose the edges of said baseboard, and means to lock said latching means to prevent the opening of said cover.

3. A lock for a typewriter-carrying-case including a baseboard and a cover, in combination, a wear-plate, having a latch-pin with an enlarged head mounted thereon, fastened to one edge of said baseboard, and latching means mounted in a wall of said cover to co-operate with said latch-pin to automatically latch said cover to said baseboard when said cover is swung down to overlap and enclose the edges of said baseboard, said latching means including a latch

movably mounted on said cover in a position to engage said latch-pin, a spring to hold said latch in operative position, and a thumb-nut to move said latch against the action of said spring and out of engagement with said latch-pin.

4. A lock for a typewriter-carrying case including a baseboard and a cover, in combination, a wear-plate, having a latch-pin with an enlarged head mounted thereon, fastened to one edge of said baseboard, latching means mounted in a wall of said cover to co-operate with said latch-pin to automatically latch said cover to said baseboard when said cover is swung down to overlap and enclose the edges of said baseboard, said latching means including a latch movably mounted on said cover in a position to engage said latch-pin, a spring to hold said latch in operative position, and a thumb-nut to move said latch against the action of said spring and out of engagement with said latch-pin, and holding means to lock said latching means to prevent the opening of said cover.

5. A lock for a typewriter-carrying case including a baseboard and a cover, in combination, a wear-plate, having a latch-pin with an enlarged head mounted thereon, fastened to one edge of said baseboard, latching means mounted in a wall of said cover to co-operate with said latch-pin to automatically latch said cover to said baseboard when said cover is swung down to overlap and enclose the edges of said baseboard, said latching means including a latch movably mounted on said cover in a position to engage said latch-pin, a spring to hold said latch in operative position, and a thumb-nut to move said latch against the action of said spring and out of engagement with said latch-pin, and holding means to lock said latching means to prevent the opening of said cover, said holding means including a bolt movably mounted on said cover and capable of being moved into and out of engagement with said latch to prevent the movement of said latch out of engagement with said latch-pin, and a spring-tumbler to engage said bolt to either hold it in engagement or out of engagement with said latch.

6. In a lock for a typewriter-carrying case including a baseboard and cover, in combination, a front escutcheon and a rear escutcheon mounted in a wall of the cover, a movable latch mounted on said rear escutcheon, a latch-actuating knob, a limit-pin to limit the movement of said latch, a latch-restoring spring, a bolt enclosed in a bolt-case mounted on said rear escutcheon, a tumbler for preventing unintentional movement of said bolt, a key-barrel to admit a key into said lock to displace said bolt, means to fasten said front and rear escutcheons to one another and to said cover, and a latch pin on the baseboard to enter a clearance recess in one of said

escutcheons to displace and be engaged by said latch.

7. In a lock for a typewriter-carrying case, in combination, a front escutcheon, having openings to admit a key, a latch-pin, and the shank of a latch-actuating knob, into said lock, a rear escutcheon, a movable latch mounted on said rear escutcheon, said latch having a hook formed on its free end to engage a latch-pin and having an inclined surface on its free end to permit it to "ride over" and be displaced by said latch-pin, a latch-actuating knob having a shank which passes through one of the openings in said front escutcheon and is fastened in said latch, a limit-pin to limit the movement of said latch, said limit-pin having an enlarged head and a reduced shank which passes through a limit-slot in said latch and is fastened in said rear escutcheon, a latch-restoring spring to restore said latch to operating position to engage said latch-pin after having been displaced by said latch-pin, a bolt having a key-slot to receive a key-bit and enclosed in a bolt-case mounted on said rear escutcheon, to be moved into and out of engagement with said latch by means of a key either to hold said latch in engagement with said latch-pin against the action of said actuating knob or to permit movement of said latch out of engagement with said latch-pin by means of said actuating knob, a tumbler in the shape of a leaf-spring and having a detent to engage tumbler-notches in said bolt to prevent other movement of said bolt than that imparted thereto by the bit of a key, a key-barrel held between said front and rear escutcheons in openings provided therefor to support a key while it is being turned to actuate said bolt, rivets to fasten said rear and front escutcheons to each other and to said carrying case, and a latch-pin to displace and be engaged by said latch.

WILLIAM A. DOBSON.
